CONDENSER WINDING MACHINE

Eugene M. Kile and Simon Kain, Chicago, Ill., assignors to John E. Fast & Company, Chicago, Ill., a corporation of Illinois

Application June 5, 1936, Serial No. 83,630

20 Claims. (Cl. 242—56)

An object of this invention is to provide a machine for winding condensers from webs of metal foil and paper which automatically grips the leading ends of the webs, winds the same on a mandrel, severs the several webs with the paper webs overlapping the metal foil webs, secures the outer ends of the paper webs, removes the wound condenser body from the mandrel, grips the outer ends of the leading webs, and repeats this series of operations indefinitely.

Another object is to provide such a machine which has a main shaft driven by a suitable source of power which drives appropriate mechanism to perform the several operations in their proper sequence, and preferably all on a single rotation of the main shaft for each condenser wound.

The metal foil must be severed before the paper web so as to cause the paper to overlap and insulate it. An object of this invention is to provide means for perforating the metal foil at a plurality of points along a transverse line, while it is in motion if desired, and after a predetermined length has been wound into the condenser.

Still another object is to provide a means actuated by the perforations when they reach a predetermined point for applying a brake to the foil beyond the perforations to cause the foil to rupture along the perforated line.

These and other objects, as will hereinafter appear, are accomplished by this invention which is fully described in the following specification and shown in the accompanying drawings, in which—

Figure 1 is a side elevation of a winding machine embodying the invention;

Fig. 2 is a front elevation of the same;

Fig. 3 is a partial enlarged front elevation showing the mandrel sections and associated parts as viewed on the line 3—3 of Fig. 1;

Fig. 4 is a partial enlarged vertical section through the mandrel operating mechanism;

Fig. 5 is a view taken on the transverse line 5—5 of Fig. 4;

Fig. 6 is a partial transverse section on the line 6 of Fig. 2;

Fig. 7 is an enlarged sectional view on the line 7 of Fig. 6;

Fig. 8 is an enlarged top plan view on the line 8—8 of Fig. 6;

Fig. 9 is a partial enlarged vertical section on the line 9—9 of Fig. 1 showing the mechanism for drawing the wound condenser off the mandrel;

Fig. 10 is a partial section on the line 10—10 of Fig. 9 showing marking and sealing apparatus;

Fig. 11 is a partial enlarged vertical section on the line 11 of Fig. 2 showing mechanism for stripping the condenser from the mandrel as well as for operating the marker and sealer;

Fig. 12 is a partial enlarged vertical section on the line 12 of Fig. 2 showing a cam for operating the stripper fingers;

Fig. 13 is a partial enlarged vertical section on line 13 of Fig. 2 showing the mechanism for severing the paper at the end of the winding operation;

Fig. 14 is a partial enlarged front elevation on the line 14—14 of Fig. 13;

Fig. 15 is a partial enlarged vertical section on the line 15 of Fig. 2 showing the mechanism for raising and lowering the mandrel;

Fig. 16 is a partial enlarged vertical section on the line 16 of Fig. 2 showing the cam for operating the locking and unlocking mechanism on the driving mandrel;

Fig. 17 is a partial vertical section on the line 17 of Fig. 3 showing the adjustable and flexible drive for the mandrel;

Fig. 18 is a modified form of brake mechanism showing a cam for applying the brakes for breaking the foil of two webs of foil simultaneously;

Fig. 19 is an enlarged transverse vertical section on the line 19 of Fig. 1 showing the braking mechanism;

Fig. 20 is a perspective of a modified form of brake cam which is connected by cable and spring so as to operate in conjunction with mechanism shown in Fig. 18;

Fig. 21 is a schematic diagram of the electric connections for providing a plurality of jump sparks for puncturing the metal foil at a plurality of points;

Fig. 22 is an enlarged partial section on the line 22 of Fig. 21 showing the jump spark points;

Fig. 23 is a front elevation of the film showing a line of perforations made by the jump sparks;

Fig. 24 is a view of the same film ruptured;

Fig. 25 is a schematic diagram of a means for applying the brake which is actuated by light passing through the perforated foil;

Figs. 26 to 32 inclusive are schematic diagrams showing various positions of the mandrel and of the webs during different stages of the winding operation;

Fig. 33 is a modified form of driving mechanism for the mandrel which enables the mandrel to be driven at a progressively faster and then a slower rate as the winding operation progresses;

nism for mechanically perforating the metal foil at a plurality of points;

Fig. 35 is a section on the line 35 of Fig. 34 showing the mechanism in an inoperative position; and

Fig. 36 is a similar section showing the mechanism in an operative position.

One embodiment illustrated comprises a machine having a table 37 supported on suitable legs 38, 39 and carrying a vertically extending frame 40. A series of drums or reels of a suitable insulating paper P, P, are mounted upon the frame as well as drums of a suitable metal foil F, F. The method of mounting these is shown in Fig. 19, and will later be described.

The two central webs of paper pass over a roller 41. One of the strands of metal foil passes over a roller 42 and the other over a roller 43. The two outside strands of paper pass over rollers 44, 45. The strands of paper are of the same width and are guided so that their ends are in the same planes. One of the strands of metal foil, however, preferably overlaps the paper insulation on one side, while the other web of foil overlaps the paper at the other side. For different types of condensers, however, the number and arrangements of webs both of paper and of foil and of their methods of overlapping and the relative widths of the several webs may be varied. The several webs then pass over guide rolls 46 and between a fixed roller 47 and a yieldable roller 48. A strand of overlapping webs 49 depends from these rollers so that it is readily engaged by a mandrel which will now be described.

This mandrel, as shown in Figs. 3 and 4, consists of a rigid mandrel section 50 and a movable mandrel section 51. These mandrel sections are raised and lowered bodily, as shown in the full and dotted line positions of Fig. 3. The mandrel section 51 is movable from the open or dotted line position of Fig. 4 to the closed or full line position. When the mandrel comes to rest in the full line position of Fig. 3, the fixed mandrel section 50 lies at the rear of the overlapping webs 49, while the movable mandrel section lies on the opposite side. By raising the mandrel sections bodily from the full line position of Fig. 3 to the dotted line position, and then by closing the movable section 51, the two sections grip the overlapping webs 49 between them. The method of raising and lowering these mandrel sections will later be described.

The fixed mandrel section 50 is carried by a fixed mandrel head 52 which is secured to a shaft 53 which is journaled in a suitable bearing housing 54 which is carried on a platform 55. This platform is movable up and down, as will later be explained, and as shown in full and dotted lines in Fig. 3, and is guided on rods 55^a slidable in guides 37^a on the table 37. The method of raising this platform will later be explained, as will also the means for gripping the outer end of the mandrel section 51. The shaft 53 is provided against endwise movement and has a bevel pinion 56 meshing with a bevel gear 57. The latter is keyed on a shaft 58 which is journaled in suitable bearings 59, 60 (Fig. 17). This shaft is driven by means of a flexible shaft 61, 62, the latter being journaled in a suitable bearing 63 on the table 37. The shaft 62 has keyed thereon a bevel pinion 64 which is driven by a bevel gear 65 on the shaft 66 which is journaled in suitable bearings 67 carried by the table 37. The shaft 66 has a pinion 68 keyed thereon which meshes with an idler 69, the latter meshing with an inter-

rupted gear 70 on the shaft 71. The shaft 71 has a sprocket wheel 72 which is driven by a sprocket wheel 73 and a sprocket chain 74. The sprocket wheel 73 is keyed on a shaft 75 which is suitably journaled in the bearings in the table supporting legs. The shaft 71 is journaled in a housing 74^a which encloses the chain 74 and is journaled at the opposite end on the shaft 75. This housing is adjustably held by means of a link 74^b having a slot 74^c through which passes 10 a bolt 74^d. The shaft 75 carries a pulley 76 which is driven by a belt 77 (Fig. 1) running over a small belt pulley 78, the latter being driven from a motor 79 through a suitable gear reduction 80. The motor is carried on a bracket 81 supported by the table legs. Thus it will be seen that with the shaft 71 running at a constant speed the mandrel shaft 53 will remain stationary part of the time, and will be driven at a constant speed for a part of the time. The proportion of the total time during which the mandrel will remain stationary will depend upon the design of the interrupted gear 70. Likewise, the number of turns that the mandrel shaft 53 will make on each revolution of the shaft 71 depends upon the gears 25 making up the gear train, but is fixed for each gear train. Also the Geneva gears 69, 70 also insure that the mandrel 50 will stop at the same position each time.

The movable mandrel section 51 (Figs. 3 and 4) is secured to a block 82 which is pivotally mounted by a pin 83 on a mandrel head 84, the latter being carried by a stub shaft 85 which is journaled in a shaft 86 which is rotatably and slidably journaled in a sleeve 87 which is carried by a support 88 on the platform 55. A rod 89 forms a reduced section of the shaft 86, and has adjustably mounted thereon a collar 90 to which is secured one end of a tension spring 91, the opposite end being connected to a yolk 92 which has 40 a straight portion 92^a slidably mounted in suitable bearings 93, and has a block 94 adjustably mounted on its opposite end. A tension spring 95 is connected at one end to the block 94 and at the other to a pin 96 on the platform 55. The yolk 92 is bifurcated and bears in an annular groove 97 in a sleeve 98, the latter being slidable over the shaft 86 and the mandrel head 84. The sleeve 98 bears against a pin 99 in the block 82. A tension spring 100 holds the pin 99 against the 50 sleeve.

The spring 95 tends to hold the various parts in the full line position of Fig. 4 in which the mandrel sections are in overlapping relation and are locked together, as will hereinafter be explained. A flexible member 101 (Figs. 1 and 6) is connected to the yoke 92 and passes over suitable sheaves 102, 103, and over a sheave 104 on a lever 105 which is pivotally connected at 106 and carries a cam follower roller 107 which bears 60 against a cam 108 on the shaft 75. The follower 107 is held against the cam by means of a spring 109. The spring 95 tends to hold the parts shown in Fig. 3 against the tension of the flexible member 101 so as to maintain the latter taut at all 65 times. As the cam 108 rotates it acts through the flexible member 101 to draw the mandrel section 51 from the position shown in Fig. 4 to the position shown in Fig. 3, and as the cam continues to rotate the spring 95 returns it to the position 70 of Fig. 4.

The mandrel head 84 is adapted to receive the end of the mandrel section 50 as it is moved to the right in Fig. 4, while the section 51 is still in the open or dotted line position due to the 75

fact that the spring 91 has forced the shaft 86 and the mandrel section 51 to the full line position of Fig. 4, but the flexible member 101 is still holding the sleeve 98 in the dotted line position of Fig. 4 in which position the mandrel section 51 is still held, all in the annular dotted line position shown. As the cam 108 continues to advance, the flexible member 101 permits the spring 95 to return the sleeve 98 to the full line position of Fig. 4, thereby moving the mandrel section 51 into the full line position of Fig. 4, at the same time gripping the outer end of the mandrel section 50.

At the same time the shaft 53 which carries the mandrel head 52 and the mandrel section 50 also carries a sliding mandrel head 110 which is slidably mounted on the mandrel head 52, and has a recess 111 adapted to overlie and engage the outer end of the mandrel section 51 in the full line position of Fig. 4 when the sliding mandrel head 110 is forced to the left as there shown. This movement takes place after the two mandrel sections are closed. The sliding mandrel head 110 has an annular groove 112 therein in which is slidably mounted a yolk 113 having a rod 114 which is slidably mounted in the bearing housing 54 and parallel to the shaft 53. A spring 115 between the housing and the sliding mandrel head normally forces the latter outwardly to the position shown in Figs. 3 and 4.

A flexible member 116 is secured at one end to the yolk 113 and passes over suitable sheaves 117, 118 (Fig. 3), and is connected to a lever 119 (Fig. 16), which is pivotally connected at 120 to the table supports. The lever 119 is held in contact with a cam 121 on the shaft 75 by means of a tension spring 122. Thus at a predetermined point in the rotation of the shaft 75, the cam 121 draws the sliding mandrel head 110 back against the action of the spring 115, and holds it there until the lever 119 suddenly drops off the point of the cam, thereby releasing the head 110 which is then returned to the spring 115 to the full line position of Fig. 4, thereby locking the end of the mandrel section 51 which has just closed to the full line position of Fig. 4. It is open just long enough to allow the mandrel section 51 to close and then be engaged.

For raising the platform 55 from the full line position to the dotted line position the platform is provided with a centrally located pin 123 which passes through the table 37 and is adapted to be engaged by a screw 124 adjustably carried by a lever 125 (Figs. 3 and 15) which is fulcrumed at 126, the opposite end being pivotally connected to a link 127. The shaft 75 passes through a slotted opening 128 in the link 127 so that the link is guided thereby. The link carries a cam follower 129 which rides on a cam 130 which is keyed on the shaft 75. Thus the platform 55 remains in the full line position for more than half each revolution of the shaft, but is raised to the dotted line position for a predetermined portion of each revolution.

Starting with the parts as shown in full lines in Fig. 3, the mandrel section 50 lies back of the depending ends 49 of the webs which go to make up the condenser. The mandrel section 51 is retracted and open as shown in dotted lines in Figs. 3 and 4. As the shaft 75 rotates, the cam 108 (Fig. 6) permits the flexible member 101 to be drawn back under the action of the springs 109 and 95, thereby forcing the shaft 86 to the right. At the same time the cam 130 (Fig. 15) passing under the follower 129 lifts the platform

55 from the full line position (Figs. 15 and 3) to the dotted line position. In the latter position the two mandrel sections 50, 51 lie one on each side of the lower ends of the webs 49. At this time the sliding mandrel head 110 (Fig. 4) is retracted, as previously described. As the yoke 92 continues to move to the right, the shaft 86 moves with it until the collar 90 strikes the sleeve 87. This fixes the movement to the right of the mandrel section 51. The mandrel head 110 then 10 is moved by the spring 115, as previously described, to lock the mandrel section 51.

As the yoke 92 continues to move to the right, it stretches the spring 91 and moves the mandrel section 51 from the dotted line position of Fig. 4 15 to the full line position, thereby causing the sleeve 97 to engage the pin 99 and to close the mandrel section 51 on the mandrel section 50. The cam 121 (Fig. 16) then releases the tension on the flexible member 116, thereby permitting 20 the spring 115 to return the sliding mandrel head 110 to the position shown in Fig. 4, in which, as previously described, it engages and locks the outer end of the mandrel section 51 to the mandrel section 50. At the same time the outer 25 end of the mandrel section 50 is locked to the mandrel section 51 in the mandrel head 84.

Following this the mandrel shaft 53 is driven by the gear chain of Fig. 17 beginning with the interrupted gear 70. The two mandrel sections 30 are locked together and are driven one from the shaft 53, the mandrel head 84 rotating on its own stub shaft 85. This stub shaft is held in the shaft 86 by means of a dog point set-screw 86^a operating in an annular groove 85^a in the 35 shaft 85.

As the mandrel sections 50, 51 rotate the paper and foil webs are wound about the mandrel, suitable tension being maintained on each web by means of brakes 131, 132, 133, 134, 135 and 136, 40 as shown in Fig. 1. As this winding continues the cam 130 (Fig. 15) rotates so as to return the platform 55 to its lowered position while the winding is continued. The winding then proceeds so long as the mandrel is driven by the 45 toothed portion of the gear 70. When the winding is nearly complete metal foil webs are perforated at a plurality of points along transverse lines by apparatus shown in Figs. 1 and 21 to 24 inclusive. Thus the foil webs F', F" pass 50 over metal guides 137 which are grounded, as indicated in Fig. 21, and have grooves 138 lying transversely of the metal web. These guides are carried on suitable metal supports 139 which are secured to the frame 40, and these carry suitable 55 insulating blocks 140 which support metal jump spark points 141 which are alternately staggered to form a row with the points immediately over the groove 138 and are spaced about .050" above the metal foil F'. Each of these points is connected through a suitable insulated lead 142 to a high resistance 143, say one megohm.

The opposite ends of these resistances are then connected to a common lead 144 which is connected to one side of a suitable source of D. C. 65 voltage 145 which is preferably of the order of 3500 volts obtained by rectifying an alternating current. The opposite side of this source is connected through a lead 146 with a brush 147 which bears on a cylindrical block of insulation 148 70 which is keyed on a shaft 149. This shaft, as shown in Fig. 1, has a gear 150 keyed thereon and meshing with a gear 151 of the same size keyed on the shaft 71. It will be understood, however, that if desired the shaft 149 may be 75

dispensed with and the block 148 placed on either of the shafts 71 or 75.

The block 148 carries a segment 148^a of copper or the like, and a grounded brush 152 bears on the block 148 and is so located that the segment 148^a will lose its contact with the brush 147 before making contact with the brush 152. A brush 153 lies midway between the brushes 147 and 152 so that the metal segment can connect the brush 153 with either the brush 147 or the brush 152. The brush 153 connects through a lead 153^a and leads 154 with a series of condensers 155, each preferably having a capacity of .02 mfd. The opposite side of each of these condensers is connected to one of the leads 142 so as to place each condenser in parallel to one of the resistances 143.

Thus as the segment rotates in a counter-clockwise direction, as shown in Fig. 21, the condensers 155 are charged, and as the segment continues to rotate it loses contact with the brush 147 and makes contact with the brush 152, thereby grounding one side of the condenser and causing it to discharge to ground on the opposite side, as shown in Figs. 21 and 22 across the gap between the points 141 and the metal foil. The resistances 143 cause all condensers to be charged about equally in a short interval of time, and prevent each condenser from discharging through other than its corresponding needle point. Without these all condensers would tend to discharge through a single point. In this way, each condenser discharges independently of the others through its own point, but they all discharge at the same time and as the points are arranged along a transverse line the discharges serve to puncture the foil at a plurality of points, as shown at F² in Fig. 23. The condensers 155 and resistances 143 are enclosed within a suitable housing 156. This provides not only a very simple device for perforating the foil and one which requires but little space between the reels, but it operates just as well with the metal web in motion as when it is at rest.

45   *Breaking the metal foil*

It is now necessary to break the metal foil just before the winding is completed so that the trailing end of the metal web will lie within 50 and be overlapped by the ends of the paper insulating webs. Also it is necessary that the ends of the paper webs shall extend beyond the metal foil webs on the advancing end of the new condenser.

55   Breaking is preferably accomplished by holding the metal webs back of the punctured line F², while the portion in advance of this line continues to be wound, thereby separating and completely severing the two, as shown in Fig. 24. 60 We prefer to accomplish this by means of light passing through the line of holes F². Thus in Fig. 25 an electric lamp 157 lighted in any well known manner is placed at a point adjacent that at which the break is to occur. A photoelectric cell 158 is placed on the opposite side of the metal web so that as the line of holes F² comes between the source of light and a slit 159 in the front of the photoelectric cell, light from the source 157 will pass into the cell 158, thereby 65 energizing it and causing it to function in a well known manner. Current from the cell 158 then passes into a suitable glow tube amplifier and relay 160 of a well known type, and this relay current passes through leads 161 to a solenoid 162 which then becomes energized and acts to

draw a cable 163 to operate a brake on the metal web, as will now be described. A switch 164 in a glow tube circuit of the amplifier is necessary to release the relay once it has been started by the photoelectric cell.

In Fig. 19 is shown the mechanism for adjustably supporting the reels, particularly for the metal webs and the brake mechanism for braking the same. This consists of an axle 168 having at one end a threaded portion 169 adapted to be screwed through a casting 170 which is secured to the frame 40 as by means of screws 171. The end 169 has a hand wheel 172 secured thereon and a locking wheel 173 is likewise screwed on the reduced portion 169. Thus a 10 very nice adjustment of the axle 168 with respect to the frame 170 is obtained. The opposite end 168^a of the axle is reduced and carries a flange reel 174 on suitable ball bearings. This reel is adapted to receive a roll of metal foil 175 20 wound on a hollow core 176 of aluminum or similar soft material, the latter having a sliding fit on the hub of the reel 174.

A disk 177 is mounted on a split collar 178, the latter with the disk 177 being adapted to be slid over the hub of the reel and to be gripped thereto. The collar carries a series of pins 179 which may be forced into the soft metal core 176 so as to lock the core and roll of metal on the reel. A clutch consisting of a stationary clutch member 180 and a movable member 181 are mounted on the axle 168, the stationary member having an arm 182 passing over a pin 183 which is carried by the frame 40. The members 180, 181 have complementary spiral surfaces, as shown in Fig. 20, and the movable member 181 bears against a collar 184 which is secured on the axle 168. The member 181 has an extension 181^a to which is secured at one side of the brake cable 163 which acts in opposition to a tension 40 spring 185.

Thus it will be seen that when the light from the source 157 passes through holes F² of the metal web and energizes the photoelectric cell 158, the solenoid 162 becomes energized and 45 draws the brake cable 163 down against the action of the tension spring 185, thereby forcing the brake member 180 with its bearing face 180^a against the flanged reel thereby stopping the metal foil and causing it to rupture at the point 50 F³ of Fig. 24.

In Figs. 18 and 20 is shown an alternative method of breaking the metal foil. Instead of the apparatus of Fig. 25 which utilizes a photoelectric cell for timing the point at which the break occurs, we have provided in Fig. 18 a timing means operated by a cam 186 on the cam shaft 75 which operates a cam follower lever 187 pivotally mounted at 188 on a member 189 slideable on a suitable bracket 190 carried by the 60 base legs and adjustably held by means of an adjusting screw 191. The lever 187 is connected to a flexible member 163^a which in this form operates to release the clutch member 181, the latter being suddenly set by the spring 185^a as 65 the lever 187 suddenly falls off the ledge of the cam 186. The cable 163^a serves to release the brake. This is just the reverse of the method of Fig. 19 where the pull of the cable set the brake and the spring 185 released it. For this 70 reason the cable and spring are placed on the opposite side of the extension 181^a. The point at which the break occurs can be very nicely timed by means of the screw 191. The reels P are similarly mounted except that no brakes for 75

stopping these reels are provided as in the case of the reels F.

Severing the wound condenser

5 After breaking the metal foil webs and just prior to finishing winding of the condenser, it is necessary to sever the paper webs. This is done by apparatus shown in Fig. 13. A cam 192 is keyed on the cam shaft 75 and serves during 10 each revolution of the cam shaft to lift a weighted link 193 which is guided at the bottom on the cam shaft and pivotally mounted at 194 to a lever 195 pivotally mounted at 196, the opposite end having an end 197 which is adapted to 15 engage an ear 198 on a member 199 rotatably mounted on an axle 200 which is suitably supported under the table 37.

The member 199 has a laterally extending finger 201 which is normally held in engagement 20 with a pin 202 on another member 203 which is likewise rotatably mounted on the shaft 200. The member 203 carries an arm 204 which passes through an opening 37b in the table 37 and through an opening 205a in a knife 205, the latter 25 being slidably mounted in a guide 206 which is suitably carried by the frame 40. The arm 204 is normally held retracted in the full line position by means of a tension spring 207, while the member 199 is normally in the position shown by 30 means of a spring 208. The knife 205 is above the level of the finished condenser so that when projected forward to the dotted line position of Fig. 13, it will sever the paper webs leaving the forward end of the next condenser hanging, as 35 shown in Fig. 26. The method of holding the outer ends of the webs of the wound condenser will presently be explained.

From the foregoing it will be seen that as the weighted link 193 rises it will depress the ear 198 40 to the lower dotted line position shown. As the end 197 slips off this ear the member will snap back to the position shown in full lines, but will be stopped by the action of the stronger spring 207. As the cam 192 continues to revolve the 45 link 193 will slip suddenly off the high point of the cam, and will drop, and as it does so the end 197 will strike the lower portion of the ear 198, thereby throwing the arm 204 forward from the full line position to the dotted line position, at 50 the same time throwing the knife 205 forward to the dotted line position, thereby severing the paper webs.

Mechanism for holding, gluing and marking the outer envelope of the condenser

55 In Figs. 9, 10 and 11 is shown apparatus for holding and gluing the outer ends of the condenser webs. A shaft 209 is journaled in suitable bearings in the table 37 and carries a lever arm 210 which is secured thereto at one end. A flexible cable or the like 211 is connected to this arm and after passing over a sheave 212 is connected to an arm 213 which carries a follower 214 which operates on a cam 215 on the cam shaft 75. A spring 210a tends to hold the lever 210 in the horizontal position shown in Figs. 10 and 11. A spring 216 holds the cam follower in contact with the cam 215.

The shaft 209 has an arm 217 which carries a 70 wick 218 to which glue or other suitable adhesive is conveyed through a pipe 219 from a suitable receptacle (not shown). The cam 215 is so timed as to force the wick 218 into contact with the wound condenser about one turn or so before it 75 is completely wound. This causes the outer lay-

ers of the paper to adhere, and also serves to hold the condenser after the webs are severed and to insure that they are pressed down so as to be held by the glue which it also applies.

At the same time a narrow band of color C' is 5 applied to the "ground" end of the condenser (Fig. 29). After severing the wick 218 continues to bear on the condenser while the lever is revolving until the winding is completed. This color is applied through a suitable wick 220 on the arm 10 217, receiving ink from a receptacle 221.

Stripping mechanism

The mechanism for stripping the wound condenser to mandrel will now be described. This 15 consists of two spaced stripping fingers 222 which are carried by a sleeve 223 which is slidably mounted on a shaft 224 adjacent the shaft 209 and parallel thereto. This sleeve, however, is keyed on the shaft 224 so as to rotate therewith. The shaft carries a lever 225, to the outer end of 20 which is secured a cable 226 which passes over a sheave 227 and is connected to a lever 228 hingedly mounted at 120, and carrying a cam follower 230 which engages the cam 231 on the cam 25 shaft 75.

Thus as the cam shaft 75 rotates the fingers 222 move from the dotted line position to the full line position of Fig. 10. In the latter position 30 they lie one on each side of the condenser C, as shown in Fig. 30. As the cam shaft continues to rotate the mandrel head 98 moves to the left, as shown in Fig. 31, thereby withdrawing the mandrel section 51 from the condenser which is prevented from moving off the mandrel section 51 by one of the fingers 222. At the same time, as has been previously explained, the mandrel section 51 swings to one side so as to be out of the way of the condenser C as it is moved longitudinally off the mandrel section 50, as shown in Fig. 32. As the upper fingers continue to move to the left, the wound condenser shown in dotted lines drops off the end of the mandrel section 50 into a suitable receptacle.

The means for moving the upper fingers longitudinally is provided, as shown in Fig. 9, by a flexible cable 232 which is attached to the sleeve 223, and passes over sheaves 233, 234 (Fig. 11) and under a sheave 235, and is then attached at 50 236 to the underside of the table 37. The sheave 235 is carried on a lever arm 237 which is pivotally mounted on the rod 120. The lever 237 carries a cam follower 238 and bears against the cam 239 on the shaft 75. Thus on each rotation 55 of the cam shaft the fingers, after moving up to the full line position of Fig. 10, are moved to the left, as shown in Fig. 32, so as to strip the condenser off the mandrel section 50. The parts are now in the position of Fig. 26, and are ready 60 to repeat the series of operations previously described.

The winding mechanism shown in Fig. 17 provides a speed of rotation for winding the condenser which is uniform throughout. For large 65 condensers, however, it is desirable that the rate of winding start slowly, increase as the winding progresses, and decrease as the winding nears completion. By using a pair of matched elliptic gears 69^b, 69^c and intermediate gears 69^a, 69^d, 70 (Fig. 33) in the gear train driving the mandrel shaft 53, the speed of this shaft can be made slow at the start, increase as the winding progresses and decrease as the winding is completed, thereby greatly decreasing the time required to wind the 75

condenser but keeping the rotative speeds low at the instant of starting and finishing.

In Fig. 34 is shown a modified form of device for perforating the metal web. This consists of a plate 240 beneath which lies a movable arm 241, which is suitably journaled as shown in Fig. 34, is mounted on a shaft 242 and carrying a spring member 243 which has a series of openings 244. A series of needle points 245 are carried by the member 241, each adapted to pass through an opening 244. The underside of the plate 240 has a recess 246 to receive these needle points. The shaft 242 carries an operating lever 247 to which is attached a flexible cable 248 which may be operated in any suitable manner not shown to cause the needle points to puncture the metal web F'. This must be done while the web remains stationary and after the metal webs have been braked.

20 To permit adjustment of the lengths of the webs, we wind the webs back and forth over rollers 41 to 45 and guide rolls 46 which are increased in number and are made adjustable so as to provide webs of different lengths for different capacity condensers. This showing is obvious and is omitted for sake of clearness. The metal guides 137 may also be made adjustable for different points of cut-off.

30 It is found that this method of winding produces condensers which run far more uniform in capacity than those wound by hand due largely to the more uniform tension on the webs, the more uniform overlap of the webs, and the more uniform lengths of the metal webs.

35 We claim:

1. In a condenser winding machine, a plurality of reels for holding webs of metal foil and paper, means for assembling these webs in juxtaposition in a predetermined order with the ends of the webs in adjacent relation, means for winding the webs including a positively driven mandrel made up of two sections adapted to receive said ends of the webs between them, means for moving at least one of said sections to cooperate with the other to grip the ends of the webs for winding the condenser, and means for disengaging the mandrel sections one at a time from the condenser when wound.

2. In a condenser winding machine, a plurality of reels for holding webs of metal foil and paper, means for assembling these webs in juxtaposition in a predetermined order with the ends of the webs in adjacent relation, means for winding the webs including a positively driven mandrel made up of two sections adapted to receive said ends of the webs between them, means for moving at least one of said sections to cooperate with the other to grip the ends of the webs for winding the condenser, and means for disengaging the mandrel sections one at a time from opposite ends of the condenser when wound.

3. In a condenser winding machine, a plurality of reels for holding webs of metal foil and paper, means for assembling these webs in juxtaposition in a predetermined order with the ends of the webs in adjacent relation, and means for winding the webs including a mandrel made up of two sections, one of which is rigidly mounted on a shaft at one side while the other is separable from the rigid section and mounted on another shaft in axial alignment with the first-mentioned shaft, the other shaft being movable endwise, so as to permit the webs to be engaged between the sections as the movable section is

5 moved to a position adjacent the rigid section for winding.

4. In a condenser winding machine, a plurality of reels for holding webs of metal foil and paper, means for assembling these webs in juxtaposition in a predetermined order with the ends of the webs in adjacent relation, means for winding the webs including a mandrel made up of two sections adapted to receive said ends of the webs between them, at least one of said sections being movable to cooperate with the other to grip the ends of the webs for winding the condenser, means for disengaging the mandrel sections from the condenser when wound, means for severing the webs at the completion of the winding operation so that the ends of the paper webs overlap the ends of the foil webs, means for separating the mandrel sections, means for bringing the ends of the webs and mandrel sections into juxtaposition to enable the mandrel sections to close on the webs, and means for closing the mandrel sections to grip the webs.

5. In a condenser winding machine, a plurality of reels for holding webs of metal foil and paper, means for assembling these webs in juxtaposition in a predetermined order with the ends of the webs in adjacent relation, means for winding the webs including a mandrel made up of two sections, one of which is rigidly mounted on a shaft at one side while the other is separable from the rigid section and mounted on another shaft in axial alignment with the first-mentioned shaft, the other shaft being movable endwise, so as to permit the webs to be engaged between the sections as the movable section is moved to a position adjacent the rigid section for winding, means for severing the webs at the completion of the winding operation, means for separating the mandrel sections, means for bringing the ends of the webs and mandrel sections into juxtaposition to enable the mandrel sections to close on the webs, and means for closing the mandrel sections to grip the webs.

6. In a condenser winding machine, a plurality of reels for holding webs of metal foil and paper, means for assembling these webs in juxtaposition in a predetermined order with the ends of the webs hanging vertically in adjacent relation, and means for winding the webs including a mandrel made up of two sections adapted to receive said ends of the webs between them, at least one of said sections being movable to co-operate with the other to grip the ends of the webs for winding the condenser, fingers movable to hold the condenser against endwise movement, means to withdraw one mandrel section from the condenser while held by the fingers, and means for moving the fingers to strip the condenser from the other mandrel section.

7. A condenser winding machine according to preceding claim 5 in which there is a common mechanism for operating all said means.

8. A condenser winding machine according to preceding claim 5 in which a shaft is operably connected to the said means to drive them to perform the several operations of winding a condenser on each rotation of said shaft.

9. The method of winding a condenser comprising leading a plurality of webs of metal foil and dielectric paper to a common point wherein they hang vertically, gripping the lower ends of said webs, winding them into a condenser, weakening the metal foil webs, holding the metal foil webs back of the line of weakening so as to cause

the foil to rupture at said line, and severing the paper web.

10. The method of winding a condenser comprising leading a plurality of webs of metal foil and dielectric paper to a common point wherein they hang vertically, gripping the lower ends of said webs, winding them into a condenser, puncturing each metal foil web at a number of points along a transverse line by a series of high potential discharges, holding the metal foil webs back of the line of weakening so as to cause the foil to rupture at said line, and severing the paper web.

11. The method of winding a condenser comprising leading a plurality of webs of metal foil and dielectric paper to a common point wherein they hang vertically, gripping the lower ends of said webs, winding them into a condenser, puncturing each metal foil web at a number of points along a transverse line by a series of high potential discharges while the web is in motion, holding the metal foil webs back of the line of weakening so as to cause the foil to rupture at said line, and utilizing light passing through the holes in one of the metal foil webs to hold the metal foil webs.

12. In a method of winding condensers, the step of weakening the metal web comprising puncturing the metal web at a plurality of points by a high potential static discharge to the metal web along a line where severance is desired, and applying tension to the metal web on both sides of the line of weakening to cause the web to rupture along this line.

13. In a method of winding condensers, weakening a metal web by producing a series of holes therein along a line of where severance is desired, passing light through said holes while the web is in motion, utilizing the light passing through said webs to hold the web back of the line of holes to cause the web to rupture along said line.

14. In a condenser winding machine, means for winding a plurality of webs of metal foil and paper, means for puncturing each metal web along a transverse line while the webs are in motion, and means operated by light passing through the punctured portion of the web to hold the web back of the line of puncture to cause the web to rupture along said line.

15. In a condenser winding machine, means for winding a plurality of webs of metal foil and paper, a plurality of points, a ground opposite said points, the ground and points lying on opposite sides of the metal web, means for energizing each point separately to cause an electric spark to jump from each point to ground simultaneously to puncture the metal foil, and means for holding the metal foil back of the line of puncture to cause the metal web to rupture along said line.

16. In a condenser winding machine, a plurality of reels for holding webs of metal foil and paper, means for assembling these webs in juxtaposition in a predetermined order with the ends of the webs in adjacent relation, means for

winding the webs including a positively driven mandrel made up of two relatively longitudinally movable sections one of which is hinged, means for moving said mandrel sections and the free ends of the webs into contact with each other, and means for disengaging the mandrel from the wound condenser.

17. In a condenser winding machine, a plurality of reels for holding webs of metal foil and paper, means for assembling these webs in juxtaposition in a predetermined order with the ends of the webs in adjacent relation, means for winding the webs including a positively driven mandrel made up of two relatively longitudinally movable sections one of which is hinged, means for moving said mandrel transversely to its axis into contact with the free ends of the webs, means for returning the mandrel to normal position after the ends of the web are engaged, and means for disengaging the mandrel from the wound condenser.

18. In a condenser winding machine, a plurality of reels for holding webs of metal foil and paper, means for assembling these webs in juxtaposition in a predetermined order with the ends of the webs hanging vertically in adjacent relation, and means for winding the webs including a mandrel made up of two relatively longitudinally movable sections adapted to receive said ends of the webs between them at least one of said mandrel sections being hinged, means for moving at least one of said sections to cooperate with the other to grip the ends of the webs for winding the condenser, means for locking the two mandrel sections against separation, and means for disengaging the mandrel sections from the condenser when wound.

19. In a condenser winding machine, a supply of paper, a supply of metallic foil, a rotatable arbor on which the paper and foil are adapted to be wound, a cam shaft and cam, and gears to produce intermittent rotation of said arbor, means for severing the foil and paper, and operating means for said severing means including a braking means for the foil having a part thereof associated with and adjustable relative to said cam for causing severance of the foil prior to the severance of the paper.

20. In a condenser winding machine, a plurality of reels for holding webs of metal foil and paper, means for assembling these webs in juxtaposition in a predetermined order with the ends of the webs in adjacent relation, means for winding the webs including a mandrel made up of two relatively longitudinally movable sections one of which is hinged, a drive shaft and gear means in connection with the mandrel adapted to produce a positive intermittent rotation thereof, means for moving said mandrel transversely to its axis into contact with the free ends of the webs, means for returning the mandrel to normal position after the ends of the web are engaged, and means for disengaging the mandrel from the wound condenser.
